No. 37,467.

Patented June 20, 1905.

UNITED STATES PATENT OFFICE.

FREDERICK W. GRELL, OF NEW YORK, N. Y., ASSIGNOR TO AMERICAN HARD RUBBER COMPANY, A CORPORATION OF NEW YORK.

DESIGN FOR A COMB.

SPECIFICATION forming part of Design No. 37,467, dated June 20, 1905.

Application filed April 6, 1905. Serial No. 254,225. Term of patent 14 years.

To all whom it may concern:

Be it known that I, FREDERICK W. GRELL, a citizen of the United States, residing at College Point, in the borough of Queens, city and State of New York, have invented a new, original, and ornamental Design for Combs, of which the following is a specification, reference being had to the accompanying drawings, forming a part thereof.

I claim—

The ornamental design for a comb, as shown.
FREDERICK W. GRELL.
